New York, N. Y., a corporation of New
York

Application January 1, 1943, Serial No. 471,039

2 Claims. (Cl. 200—80)

This invention relates to typewriting machines. The main object of the present invention is to provide an improved speed governing device for motive power means of a machine requiring a constant source of speed power.

Another object of the present invention is to provide an improved speed regulating means for the driving motor of a power operated typewriting machine or other office appliance.

An object is to provide an improved contact controlling device for the speed governing means of propulsion motors such as are commonly used to operate typewriters and other office appliances.

Other objects of the invention will be pointed out in the following description and claims and illustrated in the accompanying drawings, which disclose, by way of example, the principle of the invention and the best mode, which has been contemplated, of applying that principle.

In the drawings:

- Fig. 1 is a plan view partly in section.
- Fig. 2 is an elevation partly in section.
- Fig. 3 is a vertical section on the line 3—3 in Fig. 2.
- Fig. 4 is a vertical section on the line 4—4 in Fig. 2.
- Fig. 5 is a vertical section on the line 5—5 in Fig. 2.
- Fig. 6 is a vertical section on the line 6—6 in Fig. 4.

In Figs. 1 and 2 the reference numeral 10 designates the stator frame of an electrical propulsion motor of the type commonly used in driving office machines and appliances such as power operated typewriters. A motor of this type is provided on the well known "Electromatic" typewriter and the drawings in the present case show a motor and control means therefor suitable for use in aforesaid typewriter. It will be understood, however, that the invention may be applied to other machines or to any suitable motor without substantially changing the main features of construction which distinguish the present invention from the prior art.

The frame 10 is formed with flat sides 10a and a flange 10b which is concentric with the shaft 11 of the motor. Pressed on this flange is a shield or guard 10c which is concentric with the shaft 11 and may be made of insulating material. Secured to the flat sides 10a of the motor frame 10 is a frame comprising parallel blocks 12 of insulating material and a support plate 13 secured to the ends of the blocks 12. The opposite ends of the blocks 12 are secured to the sides of the frame 10 by means of screws 14 (Fig. 2). The

frame; comprising blocks 12 and plate 13, supports the control contacts, the speed regulating lever, and mechanism associated with said lever for controlling the contacts as will be made clear hereinafter.

The speed controlling mechanism is divided into two main groups or parts, one of which comprises a centrifugal force operated mechanism mounted on the main shaft 11, while the other 15 comprises the controlling contacts and a speed regulating lever carried by the frame including the blocks 12. The first group of parts consists of a disk 15 (Figs. 2 and 3) mounted on the shaft 11 by means of a hub 15a. Mounted on the outer 20 face of the disk 15 is a U-shaped bracket 16 pivotally supporting a lever 17. One arm of the lever 17 extends parallel with shaft 11 and is connected by a short link 18 to a weight member 19 in the form of a flat thin block or strip secured to a 25 spring 20, which is clamped to a bracket 21 secured to the outer face of the disk 15. In order to counterbalance the weight of the parts so far described the disk 15 is provided with counterbalance elements 22 riveted to the outer face of 30 said disk. These elements may be bored, milled, or filed as required to balance dynamically the assembly including the disk 15.

The other arm of the lever 17 extends substantially at right angles to the shaft 11 into a transverse slot formed in a narrow extension 15b of the hub 15a and abuts the left hand end (Fig. 2) or rear end (Fig. 3) of a pin 23 sliding in a bore in extension 15b concentric with shaft 11. The pin 23 is provided with a head 23a which limits 35 left hand movement (Fig. 2) of the pin 23.

When the motor shaft 11 rotates, the weight member 19 tends to move radially outwardly of the shaft 11 an extent commensurate with the speed of the shaft according to well known principles. In order to prevent the weight member 19 from moving too far when the motor is operated near its limit of speed, as determined by the control mechanism, there is provided a stop pin 15c (Figs. 2 and 3). The assembly including the disk 40 15 and parts carried thereby rotates within the guard 10c of the motor frame 10 as most clearly shown in Fig. 2. The outward movement of the weight member 19 in response to the centrifugal force created by the rotation of the disk 15 by 45 shaft 11 is communicated to the pin 23 by the link 18 and lever 17, whereby the pin tends to move to the right with reference to Fig. 2 as the speed increases. This movement of the pin is communicated to a contact member 24 secured 50 to a contact strip 25, the latter being provided

with an offset bent-over lug 25a (Fig. 4) on which the contact member 24 is mounted. The latter comprises a thin, narrow resilient strip of conducting material provided with a contact element 24a engaging a similar contact element on an offset lug 26a formed in a contact strip 26 which, as shown in Fig. 4, is similar in shape to the strip 25.

When the motor is at rest the contacts 24a are closed and shunt a speed controlling resistance which is placed in a suitable part of the motor circuit, in accordance with well known principles of motor control, according to the type of motor. As the speed increases, a point will be reached where the axial movement of the pin 23 in the extension 15b will be sufficient to move the head 23a into engagement with contact member 24 and separate the contacts 24a thereby opening the shunt for the resistance and reduce the speed of the motor.

Alternatively, if necessary, the lugs 25a, 26a carrying the contacts 24a may be reversed so that the movement of the pin 23 closes the contacts 24a instead of opening them. In order to accomplish this it will be merely necessary to change the extent of offset of the lugs 25a, 26a to enable the contact member 24 to be placed in front, that is, to the left (Fig. 2) of member 26a (Fig. 4).

It will be seen from the foregoing that the head of the pin 23a will take a definite position for each definite speed necessary to produce a movement of the member 18.

Motors of this type usually operate at speeds which may range from about 2800 R. P. M. to 3800 R. P. M., which requires that the spring 20 be made relatively stiff and the weight 19 light in weight in order to avoid excessive spring tension which would result if heavy weights and springs were used. By using a relatively stiff spring 20 and a small weight 19 it is possible for the governing mechanism to respond very quickly to small variations of speed. This makes it necessary that the natural period of vibration of the elements 19 and 20 on bracket 21 shall be well above the period of vibration at the highest speed, it being understood, of course, that when the motor is running at its highest speed it will tend to fluctuate above and below the desired speed which will, of course, cause the parts 19 and 20 to vibrate on the bracket 21.

Since the head of the pin 23 takes a definite position for each speed and with a slight increase in speed will move further to the right (Fig. 2) to open the contacts 24a it is possible, by adjusting the member 24 along the axis of the shaft 11 in relation to the head of the pin 23a, to adjust the speed of the motor as desired. For this purpose the contact strips 25, 26 are secured to the face of a member 27 which confronts the disk 15. The member 27 conveniently may be made of a plate of insulating material and is guided for horizontal movement along the axis of pin 23 by means of pins 18a on each side of a downward extension 27a of the plate 27.

The left hand end of screw 28 is reduced at 28a to form a shoulder and the reduced end is rotatable in a hole in plate 27. The plate 27 is confined between a loose washer 29 and a washer 30 riveted to the end of the reduced portion 28a. A cupped spring washer 31 interposed between washer 29 and the shoulder in screw 28 presses plate 27 against washer 30 but enables the screw 28 to be turned to adjust plate 27 axially of shaft 11. Thus plate 27 always is maintained in a

definite position and is prevented from chattering or vibrating on screw 28.

The screw 28 is threaded into a cam plate 34 provided with three cams 34a (Figs. 5 and 6) which are embossed in the plate to form three cam grooves 34b, the grooves being arranged concentrically of the stud 28, but so shaped that the counterclockwise ends (Fig. 5) of the grooves are axially nearer the left hand end (Fig. 6) of the stud 28 than the clockwise ends. The plate 34 is pressed against three round-nosed studs 35 radially equidistant from the screw 28 and carried by the plate 13. The studs 35 are shown in Fig. 5 as projecting into the clockwise ends of the grooves 34b and, as viewed in Fig. 5, the grooves lead counterclockwise and forwardly of the plane of the sheet, or axially of the stud 28, whereby, if the plate 34 is rotated clockwise in Fig. 5, the plate 27 will also move rearwardly of the plane of the sheet as the plate rotates. Thus the stud 28 and plate 27 will move to the right with reference to Figs. 2 and 6, and tend to move the contact element 24 away from the head 23a of the pin 23.

The position of the plate 34 shown in Fig. 5 is the one defining the lowest limit of speed in which the contact member 24 is so close to the head of the pin 23a that the member 24 will be moved to the right at a relatively low limit of speed. On the other hand, when the stud 28 is moved as far as it can go to the right in Fig. 2 by rotating the plate 34 clockwise the full extent limited by the lengths of the cam grooves 34b, the pin 23 will have to move virtually to its other limit of travel before actuating the member 24 sufficiently to open the contacts 24a. This, of course, will occur at maximum speed and the maximum centrifugal force exerted on the weight 19.

The plate 34 is rotated by means of a manual setting member or lever consisting of plate 36 (Figs. 1, 2, 4, and 5) provided with three arcuate slots 36a through which extend screw studs 37 threaded into three radially equispaced holes in the plate 13. The latter has a suitable hole large enough loosely to receive a hub 34c (Figs. 2, 5, and 6) fixed to the plate 34 into which hub is threaded the screw 28. The outer or right hand end (Fig. 2) of the stud 28 is slotted and provided with a lock nut 38 which may be screwed up against the hub 34c to lock the stud 28 against rotation relative to plate 34. Interposed between the disk 15 and the plate 13 are friction washers 39 which may take the form of simple washers of resilient material such as spring steel or phosphor bronze bent along the diameter and have sufficient friction to hold the plate 36 in any adjusted position.

For the purpose of rotating the plate 36 manually it is provided with an extension 36b (Figs. 1, 2, 4, and 5) having a pointer portion 36c bent at an angle to extension 36b. When the motor is properly installed in the machine the pointer portion 36c may cooperate with a suitable scale on the outer frame of the machine and the portion 36b extends through a suitable slot to enable the plate 36 to be moved through an angle approximately 75° limited by the lengths of the slots 36a. For the purpose of holding the plate 36 in contact with the pins 35 there are secured to the plate 36, intermediate the ends of the slots 36a, three leaf springs 40 (Figs. 2 and 5) which press on the plate 34 near screw 28 and thus tend to press the plate to the right in Figs. 2 and 6 against the studs 35 which are rounded to conform to the shape of grooves 34b in trans-

verse section. The plate 34 is keyed to the plate 36 by means of lugs 36d which are bent at right angles to the plate 36 and extend into slots 34d in the edges of plate 34.

Owing to the fact that the plate 27 is frictionally mounted on the end of the screw 28, the position of the contact member 24 may be initially adjusted relative to the head 23a of stud 23 by loosening the lock nut 38 and rotating the screw 28 by means of a screwdriver. This causes the plate 27 to move to right or left (Fig. 2) as the case may be relative to the plate 34. Thus if the lower limit of speed should be determined as 2800 R. P. M., the stud 28 may be turned until the contacts 24a barely open with the manual 15 setting member 36b in the position of Fig. 5. Obviously it would be useless to adjust the contact member 24 to the point where the contacts 24a open at some lower speed as they would make it impossible to obtain the maximum speed allowed by the range of movement of plate 38.

In order to avoid the use of soldered connections which might be broken from vibration, the contact strips 25, 26 are provided with lugs 25b, 26b (Figs. 1 and 4) which extend into slots 12a (see Fig. 2 also) formed in the plates 12 and extending parallel with the axis of rotation of the motor. The ends of these lugs bear against contact strips 41 secured in the slots 12a and having at their ends resilient portions 41a to maintain good contact with the lugs 25b, 26b and also with members 42 such as buttons insulatably mounted on the motor frame 10 and connected to the motor circuits. This method of making connections between the governor controlled contacts 24a and the motor circuits makes it possible to disassemble the mechanism without unsoldering any connections and also provides a more rugged connection which is not easily disturbed.

One of the practical advantages of the governor described herein is that all of the electrical connections and speed regulating parts are wholly external of the centrifugal force responsive elements of the system. In prior art the contacts are mounted on the disk 15 requiring that electrical connections be made by means of a commutator device. These commutator devices not only increase the cost of the device but create a great deal of trouble in service owing to de-

terioration of the brushes and commutator segments.

While there have been shown and described and pointed out the fundamental novel features of the invention as applied to a single modification it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

15 1. A speed responsive switch for use with rotary mechanism having a switch actuating member centrifugally displaced along an axis of rotation, comprising a support screw disposed axially of said member, manual adjusting means 20 mounting said screw in said frame including a manual member movable to select a speed, a support plate mounted on the end of said screw confronting said member, said plate being adjustable axially of said member by rotating said screw; and contact means mounted on said plate 25 and including a contact member in axial alignment with said member and actuated thereby, said plate and said screw being bodily movable toward and away from said member when said 30 manual adjusting means is operated to select a speed.

2. A speed responsive switch for use with rotary mechanism having a switch actuating member centrifugally displaced along an axis of rotation, comprising a support plate disposed 35 transversely of and confronting one end of the actuating member, a second support plate mounted between said member and the first plate, contact means mounted on said second plate and including a contact element actuatable by said member with changes in the motor speed; and means for mounting said second plate on the said first plate for movement axially of said member, including a manually adjusting member and an adjusting screw bodily movable axially of the actuating member by said adjusting member, said second plate being mounted on the 40 end of said adjusting screw.

RICHARD VON REPPERT.
